UNITED STATES PATENT OFFICE.

ROBERT J. ANDERSON, OF SIDNEY, OHIO.

WASHING-MACHINE TUB.

1,389,090.

Specification of Letters Patent. Patented Aug. 30, 1921.

Application filed August 16, 1917. Serial No. 186,622.

To all whom it may concern:

Be it known that I, ROBERT J. ANDERSON, a citizen of the United States, residing at Sidney, in the county of Shelby and State 5 of Ohio, have invented certain new and useful Improvements in Washing-Machine Tubs, of which the following is a specification.

My invention relates to washing machine 10 tubs, especially of the character of those mounted for rocking or vibrating movements, and it is the object of my invention to provide a tub of novel construction whereby to obtain great strength and durability.

My invention consists in forming a tub which is substantially elliptical in cross-section in a plane perpendicular to its pivotal axis; further, to so construct a washing machine tub having end-walls, staves and tension-bands, that pressure of the tension-bands about the end-walls acts upon the end-walls and upon the portions of the staves 20 between the end-walls to normally press 25 those portions of the staves between the end-walls inwardly; further, to provide novel means for forming and connecting the boundary walls of the tub-opening; and, further, to provide novel arrangement of 30 the interior faces of the walls of the tub-opening and cover therefor.

The invention will be further readily understood from the following description and claim, and from the drawings, in which 35 latter:

Figure 1 is a plan view of a washing machine tub embodying my invention.

Fig. 2 is a longitudinal vertical section of 40 a washing machine tub embodying my invention, with the cover removed, and taken in the plane of the line 2—2 of Fig. 1.

Fig. 3 is a vertical cross-section of the same, taken in the plane of the line 3—3 of Fig. 2.

Fig. 4 is a detail in vertical longitudinal section, showing the tub-opening and its cover, and taken in the plane of the line 2—2 of Fig. 1.

Fig. 5 is a cross-section of the same, partly 50 broken away, taken in the plane of the line 3—3 of Fig. 2.

Fig. 6 is a horizontal section taken in the plane of the line 6—6 of Fig. 2.

Fig. 7 is a detail in section, taken in the 55 plane of the line 7—7 of Fig. 6; and

Fig. 8 is a detail taken in the plane of the line 8—8 of Fig. 3.

My improved washing machine tub is preferably elliptical in general form. The body of the tub is shown at 11. It is provided with an opening 12 through which the contents of the tub are received and removed. The tub comprises end-walls 13 and staves 14, 15, the staves 15 being at the opening 12. The end-walls and staves are instanced as 60 of wood, but may, if desired, be of other material. The respective end-walls are substantially elliptical in outline, the elliptical peripheral edge 16 of the end-wall being interrupted by an extension 17 extending 65 upwardly in the plane of the end-wall.

The staves extend crosswise of the end-walls, the outer ends of the staves overhanging the outer faces of the end-walls. The end-walls and staves are provided with overlapping joints. Thus, the inner faces of the staves 14 are provided with grooves 18 adjacent to their ends, in which the peripheral edges of the end-walls are received. The joints between the staves are preferably lap- 70 ping joints, being shown as tongue and groove joints 19. The staves 15 preferably form the side boundaries or walls of the opening 12 of the tub. They are instanced as provided with longitudinally extending 75 enlargements 20 to the opening, their inner faces sloping inwardly, as shown by the inner sloping faces 22, to direct the moving contents of the tub inwardly away from the opening during operation. The edges of 80 the staves 15 at the opening 12 slant inwardly toward each other, as shown by the slanting faces 23, for forming a tapering joint between said side walls of the opening and the relatively tapering side walls 24 of 85 the cover 25.

The end-walls are provided with recesses 29 in their peripheral edges at the respective ends of the extensions 17, in which the enlargements 20 of the staves 15 are received. The inner sloping faces 22, of the staves 15 are, adjacent to their respective ends, provided with grooves 31, and the slanting faces 23 are, adjacent to their respective ends, provided with grooves 32, the 100 mating peripheral edges of the walls of the recesses 29 and extension 17 being received respectively in the grooves 31, 32, when said end staves 15 are in place, forming a lap- 105 ping water-tight joint at each of the cor- 110

ners of said opening, the staves 15 which form the side walls of said opening extending beyond the end-walls of the tub, further aiding in strength of the tub.

5 The staves 14 are received about the peripheral edges of said end-walls, the staves 15 forming end-staves of said tub and the side walls of the opening 12 of the tub. The outer faces of said staves are preferably 10 flush with the outer peripheries of the extensions 17. The peripheral edges of said extensions and the outer peripheral faces of said staves preferably form a continuous ellipse. The respective ends of the staves 15 preferably extend outwardly slightly beyond said end-walls.

In operation, the tub is suitably mounted and operated so as to have a pivotal axis or axis of oscillation which is perpendicular 20 to the end-walls of the tub.

The end-walls of the opening 12 are preferably formed by reinforcing strips 36, which are secured to the inner faces of the extension 17 by screws 37. The inner faces 25 of these reinforcing strips are preferably slanting, as shown at 38, coacting with correspondingly slanting end-faces 39 of the cover. The ends 40 of said reinforcing strip preferably abut against the inner slanting faces 23 of the side walls of the opening and 30 coact with the same in forming the corner of the tub-opening.

Reinforcing strips 41 are secured to the outer faces of the extension 17, as by screws 35 42. The ends 43 of the reinforcing strips 41 preferably abut against the slanting face 23 of the staves 15 outside the end-walls, and coact with said slanting face to strengthen 30 the corner of the tub-opening.

40 The outer peripheral edges of the reinforcing-strips 36 and 41 preferably lie in the plane of the outer periphery of the extension 17. Said reinforcing-strips may be of wood, the grain of the wood extending 45 crosswise of the direction in which the grain of the extension 17 extends. The outer faces of the reinforcing-strips 41 are flush with the outer ends of the staves.

The cover is preferably a sheet-metal 50 cover, having the sloping side walls 24 which correspond with the slanting faces 23 and coact therewith, and with the sloping end-walls 39 corresponding with the slanting inner faces 38 of the end-walls of the 55 opening 12, and coact therewith, the said side walls 24 and end-walls 39 being connected by an inner closing wall 47 and an outer wall 48. The inner edges of the side and end walls of the cover, when the cover 60 is in place, are preferably coincident with the inner edges of the slanting faces 23 and 38, so that contact of the water and contents of the tub with the faces 23 and 38 will be avoided, thereby preventing seeping or spraying of water between the cover and

the walls of the tub-opening. The cover is also preferably provided with side flanges 50 and end flanges 51, received respectively over the edges of the staves 15 and the reinforcing strips 36. As hereinbefore stated, 70 the inner sloping faces 22 further deflect the contents of the tub away from the outer faces of the walls of the tub-opening.

It has been found in practice that tubs which are mounted to swing and are formed 75 of staves are very liable to leakage. I have avoided this objection by the manner in which the staves and end-walls are formed and connected, and, furthermore, by providing bands received about the end-walls 80 in such manner as to cause pressure upon the staves between the end-walls toward the inner portion of the tub. For this purpose I provide the bands 53, which are preferably slightly flexible sheet-metal bands, one 85 of the bands being provided about each of the end-walls of the tub, and extending inwardly from said end-walls for overhanging the planes of the inner faces of said end-walls and thereby exerting inward pressure 90 upon the staves between said end-walls. The said bands extend lengthwise of the end-walls and of the extensions of said end-walls at the opening of the tub.

A suitable tensioning device is provided 95 for each of the bands. This tensioning device is shown formed by providing the respective ends of the band with cheeks 54, 55, secured to the ends of the band by rivets 56. A bolt 57 is received through holes 58, 100 59, in said cheeks and has a nut 60 adjustably received over its threaded end. The middle of the width of the band and the tension-device are substantially in the plane 105 of the inner face of the end-wall of the tub, so that, when tension is exerted on the band, the latter will tend to tilt inwardly at its inner edge for exerting inward pressure upon the portion of the staves between the 110 end-walls, tending to bow the staves between the end-walls of the tub inwardly for compressing the joints between the staves and aiding in resisting outward pressure.

The outer edges of the bands coincide 115 preferably substantially with the planes of the outer faces of said end-walls.

The pressures of the bands tend to maintain the joints between the staves closed and to compensate for the expansion and contraction of the staves due to the changes in 120 atmosphere and moisture. The pressures of the bands upon the staves also act to resist the outward thrusts of the contents of the tub upon the staves during operation of the tub. The pair of tension bands, one received about each of the end walls and extensions, at the respective ends of the tub, are 125 the sole tension bands employed by applicant, as the presence of additional tension bands between the end tension bands would 130

- detrimentally affect the inward pressures exerted. The inward pressures of the inwardly overhanging edge of the tension band at each end of the tub coact to afford 5 the desired inward pressure throughout the lengths of the staves between the end walls, the pressure of the outer portions of said tension bands being resisted by said end walls and extensions.
- 10 The cover is provided with suitable handles 61. The flanges of the cover are received between the bands 53.
- Spiders 62 have arms 63 extending in various directions across the outer faces of the 15 end-walls of the tub, for reinforcing these end-walls, the inner faces of said spiders contacting said outer faces. The spiders are secured to the tub by means of screws 64. The spiders are preferably comparatively 20 thin, flat castings of metal which are secured to the end-walls and aid in preventing warping of said end-walls and in imparting strength and durability to the end-walls of the tub.
- 25 I do not herein claim the form of the interior surface of the tub, or the manner of pivoting the tub with relation to said interior form, or the manner of mounting or operating the tub, or a plurality of said 30 tubs, having shown, described and claimed the same in copending applications for patents filed by me in the United States Patent Office as Serial No. 186,623, filed August 16, 1917, and Serial No. 187,598, filed August 22, 35 1917.

What I claim as new in the present application, desired to secure by Letters Patent, is:

In a washing machine tub having an open-

ing, the combination of an end wall at each 40 end of said tub, staves received about said end walls and comprising an end-stave provided with an inward extension at each side of said opening, said end-staves forming the side walls of said opening, each of said end-walls provided with an extension at said opening between said end-staves, each of said end-staves at each end thereof provided with a groove at its inner face presented toward the inner part of said tub 50 and with a groove at the side thereof presented toward said opening, the peripheral edge of said end-wall and the lateral edge of said extension received in said respective grooves at each corner of said opening, a 55 reinforcing strip at each side of each of said extensions, the end of each of said reinforcing strips at each of said corners abutting against the side of said end-stave at each of the corners of said opening, said 60 reinforcing strips and said edge of said extension at each of said corners forming a lapping tongue and groove joint with the side of said end-stave at each of said corners, and a tension band received about each end 65 of said tub in the plane of said end wall for forcing said ends of said extensions into said grooves coacting therewith and forcing said abutting ends of said reinforcing strips and said sides of said end staves toward one another, for the purpose described.

In testimony whereof, I have hereunto signed my name in the presence of two subscribing witnesses.

ROBERT J. ANDERSON.
